UNITED STATES PATENT OFFICE

CHARLES L. HUSTON, OF COATESVILLE, PENNSYLVANIA.

POURING-HEAD FOR INGOT-MOLDS.

1,240,722.

Specification of Letters Patent. Patented Sept. 18, 1917.

Application filed June 27, 1916. Serial No. 106,159.

To all whom it may concern:

Be it known that I, CHARLES L. HUSTON, a citizen of the United States, and a resident of Coatesville, county of Chester, State of Pennsylvania, have invented certain Improvements in Pouring-Heads for Ingot-Molds, of which the following is a specification.

My invention relates to certain improvements in pouring heads used in pouring ingot molds which are supplied with metal from the bottom.

One object of my invention is to construct the pouring head so that a greater portion of the gas will escape from the molten metal before it is carried down into the passageways leading to the molds by the metal, resulting in the casting of a more perfect ingot than heretofore.

20 A further object of the invention is to provide a pouring head with means by which the gases will freely escape from the molten metal at different points throughout the height of the pouring head.

25 In the accompanying drawings:—

Figure 1, is a sectional view, on the line 1—1, Fig. 2, of a bottom plate with a nest of ingot molds mounted thereon and my improved pouring head in position;

30 Fig. 2, is a plan view;

Fig. 3, is an enlarged sectional plan view on the line 3—3, Fig. 1;

Fig. 4, is an enlarged sectional plan view on the line 4—4, Fig. 1;

35 Fig. 5, illustrates a view of my improved pouring head in which special bricks are used;

Fig. 6, is a sectional plan view on the line 6—6, Fig. 5;

40 Figs. 7, 8 and 9, are perspective views of the special bricks used in lining my pouring head, as illustrated in Fig. 5; and

Fig. 10, is a view of a modification.

Referring to Figs. 1 to 4, inclusive, 1 is a bottom plate having channels 2 in which are located tubular channel bricks 3 through which the molten metal flows from the pouring head to the several ingots. These channels in the bottom plate may be arranged in any manner desired without departing from the essential features of the invention. The bottom plate may be round or square, or other shape, depending upon the desired nesting of the ingot molds.

45 In the present instance, the pouring head 4 is mounted at the center of the plate, as

clearly shown in Fig. 1. 5 is the casing of the pouring head which is made in two parts 6 and 7 secured together by bolts 8 which pass through slots in the flanges at the opposite corners, as clearly shown in Fig. 3. The casing is lined with bricks 9, either of special form, as illustrated in Fig. 5, or of the ordinary rectangular form illustrated in Fig. 1. The bricks are so built as to form a vertical 65 pouring channel 10 and a gas exhaust channel 11. This gas exhaust channel is connected at intervals by cross passages, as at 12, 12^a and 12^b, with the pouring channel 10 so as to allow for the escape of gas from the 70 metal as it flows through the pouring channel.

The metal, as it flows down, strikes the base 13 and is deflected into the lowest passage 12, which communicates with the passages in the channel bricks 3 and flows through these passages and into the bottom of the ingot molds 14, the molten metal rising in these ingot molds until it reaches the proper height. The molten metal striking 80 the bottom of the pouring opening splashes to a certain extent and allows the gas to escape into the gas channel 11 and, if the lower portion of the pouring channel should become filled with molten metal, the metal 85 will flow through the second channel 12^a and down through the gas passage, while the gas will escape up through the said passage.

The fountain 15 may be of any form desired so as to properly direct the metal from 90 the ladle into the pouring head.

By the above construction the major proportion of the gas escapes before reaching the ingot molds and, consequently, comparatively little gas enters the molds, producing 95 a more solid ingot than by the ordinary process of pouring.

By making the pouring head in the manner illustrated in Figs. 1 and 3, I am enabled to use the ordinary rectangular bricks 100 and waste fragments of bricks. In building the pouring head, one-half of the casing 4 is laid in a horizontal position and the bricks are built up on it so as to provide the two channels 10 and 11, then the other section is clamped to it and the structure raised in the proper position so that it will communicate with the channels in the bottom plate.

I preferably make the pouring channel 110 less in area than the gas channel so as to allow the gas freedom to separate from the

molten metal and to escape, as the metal is poured.

In the construction illustrated in Figs. 5 to 9, inclusive, the lining bricks are made in special shapes. In this instance, the two parts 5^a and 6^a of the casing are secured together at opposite sides and the casing is made tapered in cross section to accommodate the shape of the bricks illustrated in Figs. 7, 8 and 9, as the gas channel 11^a is of a proportionate greater diameter than the pouring channel 10^a. The bricks 9^a, illustrated in Fig. 7, have two channels extending through them, while the brick 9^b, Fig. 8, has a single channel and is used to form cross channels 12^c. The brick 9^c has a single opening and is used at the base of the pouring head and this opening is in line with the gas openings above and forms a communication between these openings and the channels in the base.

In using my improved pouring head, it is placed on the bottom plate in line with the center opening communicating with the several channels in the base and the several ingot molds are arranged over the channels in the base in such a manner that each mold will be supplied with molten metal from the pouring head. The fountain is placed on the pouring head and as the molten metal flows through the fountain to the pouring head it will pass through the channel 10 and will strike the bottom of the channel, splashing to a certain extent, and allowing the gas to escape through the channel 11. The molten metal will flow into this channel and into the channels in the bottom plate to the bottom of the several ingot molds and will rise as the metal continues to flow into the pouring head. As the metal flows into said head the gas, as it is carried with the metal, escapes not only through the bottom lateral passage 12, but also through the lateral passages 12^a and 12^b, there being three lateral passages in the present instance.

If, as remarked above, the surface of the molten metal in the pouring head reaches the lateral passage 12^a, then it will flow through this passage and down into the channels in the base, the gas escaping from the metal through this passage, while the lower passage is closed, due to the molten metal accumulated in both vertical channels. The pouring is continued until the metal reaches its proper height in the ingot molds, when the flow is discontinued, and the fountain removed, and before the molten metal is finally set the pouring head is loosened from the base and is also removed. It is then dismantled, the bricks discarded and a new set of bricks built in the casing.

In Fig. 10, I have illustrated a modification of the invention, in which a cross passage 12^d is located in a base section at the bottom of the pouring head 4^b.

While my invention is particularly adapted for use in connection with the pouring of molten metal into ingot molds, it will be understood that it can be used for pouring metal into other types of molds without departing from the essential features of the invention.

I claim:

1. The combination in a pouring head of two vertical channels, one for molten metal and the other for gas, said channels communicating at intervals along their length.

2. The combination in a pouring head of two vertical channels, said channels communicating at their base, and having a second communicating passage at a point above the base.

3. The combination with a base plate having passages communicating with a plurality of molds, of a pouring head comprising two vertical channels, one for molten metal and the other for gas, said gas channel communicating directly with said passages and said metal channel communicating with the gas channel at a point above the base plate.

4. The combination with a base plate having passages communicating with a plurality of molds, of a pouring head comprising two vertical channels, one for molten metal and the other for gas, the gas channel descending directly into said base plate passages, the metal channel ending its vertical descent at a point above the base plate, a lateral passage connecting the lower end of the metal channel with the gas channel, and a lateral passage connecting said channels at a point above said first named lateral passage.

5. The combination in a pouring head, of a casing made in two parts; means for detachably holding the parts together; lining bricks mounted within the casing and forming two vertical channels; one channel being of a greater diameter than the other; and transverse passages connecting the two vertical channels at points between the bottom and the top of the pouring head.

6. The combination in a pouring head, of a casing consisting of two sections having flanges at opposite corners, the flanges being slotted; bolts located in the slots for holding the sections together; a brick lining built in the casing and forming two vertical channels, one channel being greater in diameter than the other; and cross passages connecting the vertical channels between the upper and lower ends of the pouring head.

7. The combination in a pouring head, of a casing; a series of molded bricks mounted within the casing, certain of these bricks having two openings therein and others having a large single opening so that, when the bricks are assembled, there will be

formed two vertical channels and a connecting transverse passage.

8. The combination with a base plate of a pouring head comprising a casing made in two parts; a series of molded bricks located within the casing, certain of the bricks having two openings, one opening being of greater diameter than the other, others of the bricks having a large single opening forming a lateral communication between

the two vertical channels formed by the other bricks; a base brick having a single opening in line with the large vertical channel and forming an abutment for the molten metal as it flows into the smaller channel, the 15 opening in this last mentioned brick forming a communication between the opening in the vertical channels and the opening in the base plate.

CHARLES L. HUSTON.
